UNITED STATES PATENT OFFICE.

JÁNOS KRISZT, OF BUDAPEST, AUSTRIA-HUNGARY, ASSIGNOR TO JOZSEF ARAK, OF KISPEST, AUSTRIA-HUNGARY.

CHARCOAL FLAT-IRON.

1,040,216.

Specification of Letters Patent.

Patented Oct. 1, 1912.

Application filed November 10, 1911. Serial No. 659,592.

To all whom it may concern:

Be it known that I, JÁNOS KRISZT, a subject of the King of Hungary, and resident at VIII Tömöuka 33, Budapest, Austria-Hungary, have invented certain new and useful Improvements in Charcoal Flat-Irons.

This invention relates to improvements in charcoal heated sad irons and has for one of its principal objects the use of transmitting means, preferably in the form of studs, for transmitting heat from the fuel bed to the bottom of the iron.

The invention will be more fully described in connection with the accompanying sheet of drawing and will be more particularly pointed out in and by the appended claims.

In the drawing: Figure 1 is a longitudinal vertical section of a sad iron embodying one form of my invention. Fig. 2 is a horizontal sectional view thereof. Fig. 3 is a rear elevation thereof.

Like characters of reference designate similar parts throughout the different figures of the drawing.

As illustrated, the device of my invention includes a hollow ironing body provided with a fuel grate *b*, having the usual grate openings *b*². The bottom wall *a'* of the iron is provided with transmitting studs *a* which are disposed in spaced relation with respect to each other and which project into the openings *b*² sufficiently to enter the fuel bed thereon and effectively transmit heat to the bottom *a'* of the iron. As illustrated, the studs *a* project slightly above the upper face of the grate *b*. The grate *b* has an upwardly projecting portion *b'* which is attached to a portion of the iron at *b*³. It will thus be seen that a suitable space is provided below the grate *b* to receive the ashes, and to which space suitable draft openings *h* lead, the heat transmitting studs extend-

ing through such space to effectively transmit the heat to the bottom of the iron. 45

The rear wall of the iron, *a*² is provided with an ash discharge opening *a*³ adapted to be closed by a sliding closure or gate *c* provided with a hinged handle *f*. 50

The iron is provided with a cover *a*⁴ hinged at *a*⁵ and having a suitable fastening device *a*⁶. The cover *a*⁴ is provided with a suitable lug *a*⁷ to receive the handle *f* when the latter is disposed in the position shown in dotted lines to retain the gate *c* in an open position. 55

The gate or closure *c* is provided with a lug *e* adapted to engage the wall portion *a*² to limit the opening movement of the closure. 60

I claim:

1. A sad iron comprising in combination, a hollow ironing body provided with an ash discharge opening, and a grate above the bottom wall of said body having grate 65 openings therein, said bottom wall having heat transmitting studs projecting into the grate openings and slightly above the grate to enter the fuel bed thereon, said studs being wedge shaped on that side thereof opposite said discharge opening, substantially as described. 70

2. A sad iron comprising in combination, a hollow ironing body and a grate above the bottom wall of said body having grate 75 openings therein, said bottom wall having heat transmitting studs projecting into the grate openings and entering the fuel bed thereon, substantially as described.

In testimony whereof I have hereunto set 80 my hand in presence of two witnesses.

JÁNOS KRISZT.
